FIG 3

Inventor:

W Gilman Snyder Jr.

UNITED STATES PATENT OFFICE

1,977,296

TIME SWITCH

William Gilman Snyder, Jr., Jackson, Calif.

Application September 24, 1932, Serial No. 634,742

4 Claims. (Cl. 200—36)

This invention relates to devices used for the purpose of controlling any other device in synchronism with time.

Its primary object is to provide for the making or breaking of electric circuits at any predetermined time or times, but, certain other obvious and useful functions will hereinafter become apparent from the description and appended claims, as well as from the accompanying drawing.

Essentially the invention is a simple mechanism for controlling two operations, such as for closing and then opening an electrical circuit after any desired interval of time, by providing a group of electrical contactors for an entire period, such as for a day of 24 hours, of a number determined by the shortest division of the period it is desired between operations, and then, a means for selecting a certain one of these contactors for the closing operation, and a certain other one for the opening operation. A special relay is provided to facilitate the closing and opening operations by means of electromagnets controlled thru the electrical contactors, and further, to insure a unidirectional cycle of operation of the switch.

More specifically, and in detail, the arrangement and functions of the component parts of the invention will be discussed.

One form of the invention is illustrated in the accompanying drawing, in which: Figure 1 is a plan view of the arrangement of the contactors. Figure 2 is a frontal view of the supporting structure and certain dials, with portions of them shown as cut away to better illustrate the relation of the contactors in back of them. Figure 3 is a view in perspective of one of the contactors before assembly on a proper shaft. Figure 4 is a plan view of the special relay. Figure 5 is a view of the relay as presented from the right in Figure 4, and is intended to show primarily the construction and mounting of the relay armature so the intervening electromagnet and structure do not appear. Figure 6 is a view of the relay structure as it would appear from the bottom in Figure 4.

Reference to Figure 1 will show that three identical groups of electrical contactors are provided, each group being arranged as a helix about a shaft, and with the individual contactors displaced from one another by equal angles, of a magnitude such that in the axial length of the helix one revolution is described.

Group 1 of the contactors will, for convenience, be termed the rotating contactors, as it

is intended that they shall continuously rotate in a clockwise direction, being driven thru the spur gears 2 and 3, by means of a suitable synchronous motor, or clock motor, acting upon the driving shaft 4. For the case at hand, it is intended that the driving shaft 4 will be directly connected to a suitable clock motor, and will rotate once every twelve hours. The ratio of the gears 2 and 3 is to be such that the rotating contactors will revolve once for every two revolutions of the driving shaft, or once in twenty-four hours. If twenty-four contactors are provided, there is thereby one for every hour of the day, with the contactors displaced from one another by equal angles, and each describing one revolution every twenty-four hours.

It is to be understood that neither the speed of revolution of the contactors, nor their number, is limited to those values just indicated, because it is readily conceivable that particular purposes would justify others.

The second group of contactors, designated as 5, shall be termed the starting contactors because it is thru one of them and thru one of the rotating contactors that the starting operation shall take place. These starting contactors are so mounted as to be rotatable by hand, in such a manner that any one of them may be brought into position along a certain desirable axial length of the shaft, which will hereinafter be indicated, and there left. The dial 6 is provided for this purpose and it is to be noted that a suitable scale of figures is an indication of the location of any particular contactor. Those figures above the black guide line might be chosen to indicate the hours from midnight until noon, and those above the white guide line might be used to indicate the hours from noon until midnight.

The third group of contactors, designated at 7, shall be termed the stopping contactors inasmuch as it is thru one of them and thru one of the rotating contactors that the stopping operation will take place. These stopping contactors are mounted in exactly the same manner as the starting contactors, and they may be rotated by hand by means of the dial 8.

Reference to Figure 2 will show that the starting and stopping contactors are mounted about axial centers diametrically opposite each other, with the rotating contactors about a center midway between. The starting contactors are placed near enough the rotating contactors so that at the circumferential point 9 a slight overlap might occur between the ends of a starting

contactor and a rotating contactor which might be in a position to touch at that point. The same is true of the stopping contactors at the circumferential point 10.

5 It is apparent that, inasmuch as the rotating contactors are continually rotating, there will periodically be in position at both circumferential points 9 and 10, a different rotating contactor, which will have a specific position along 10 the axial lengths at these points. For instance, assume that the rotating contactor designated 7 is at point 9. One hour later the contactor designated 8 is in place at point 9, and at a position in space different from that which the first 15 contactor maintained, due to the helical arrangement of the contactors about their shaft. There is thus provided a means for selecting which rotating contactor may be made to contact with a starting contactor, merely by dialing 20 the proper starting contactor into place.

As shown in Figure 2, the starting contactor 7 is in place at point 9. Assuming that the time is six o'clock and that the rotating contactors were properly started, then the rotating contactor designated 6 would be at point 9, but nothing would happen because the contactors would not touch each other due to their different position in space. However, at 7 o'clock the rotating contactor 7 would have come into position 30 at point 9 and would touch the starting contactor, thereby providing a means for completing the starting operation.

For the stopping operation the same sort of reasoning will apply. Reference to Figure 2 will 35 show that the stopping contactor designated 8 is shown as in position at the point 10. Nothing will happen until one hour after the starting operation has transpired, when the rotating contactor 8 will have moved to point 10, thereby 40 providing a means for achieving the stopping operation.

It will be noted that at the same time a rotating contactor and a stopping contactor are in position for the stopping operation, a rotating contactor may simultaneously be in position to touch a starting contactor at some circumferential point as that indicated at 11. Such would be the case if the starting operation had occurred at 7 o'clock, as shown, with 45 the stopping operation intended for 8 o'clock. It is evident that at 8 o'clock a rotating contactor and a starting contactor would be in such relation to each other, at the circumferential point 11, as to touch. No stopping operation could arise as a result, unless some means were provided to nullify the effect of the starting contactor being in contact with a rotating contactor. This is achieved by the provision of 50 a special relay which insures that once a starting operation has been completed no further action can transpire until a stopping operation has taken place.

Reference to Figure 4 will aid in comprehending the particular action. In conjunction with such action, it will be observed from Figure 1, that battery is constantly applied to the rotating contactors, thru the brush 12 bearing upon a face of the spur gear 2. If a rotating contactor is touching a starting contactor, as at point 9, there is thus provided a means for completing an electrical circuit thru the contactors, the brush 13, the relay lugs 14 and 15, (Figure 4), the electromagnet 16, and the lug 17, back to battery. The electromagnet 16 will 70 exert a pull upon the armature 18 of the relay,

which is normally at rest against the pole piece of the electromagnet 19, and in this position is under a longitudinal compressive force due to the action of the flat spring 20 acting thru the member 21. Under the attraction of the electromagnet 16, the armature 18 will move over against the face of the pole piece of the electromagnet 16, and will remain there because of the disturbance of the alignment of the compressive force acting upon it. 80

When the armature so moves it contacts the lug 22 of the relay, and a means is thereby provided for the completion of an electric circuit thru the armature, to ground, to battery, and to lug 22. It is further intended that the lug 22 shall be of sufficient resiliency to move, when contacted by the armature, and to act thru the insulating member 23 upon the lug 14 in such a manner that it too will move and open the circuit thru the electromagnet 16. 85

As a result, no current will flow thru the electromagnet 16 until the armature has been returned to normal by action of the electromagnet 19. This electromagnet 19 may be energized as the result of a stopping contactor touching a 90 rotating contactor thereby closing an electrical circuit from battery, thru the contactors, the brush 23, the relay lug 24, (Figure 4), the electromagnet 19, and the relay lug 17 back to battery. 95

It is obvious that only a portion of the many forms in which this invention may be embodied have been discussed herein, and it is to be understood that the invention is not limited to those specifically indicated but may readily be 100 employed in various manners without departing from the spirit of the invention or the scope of the appended claims.

Having thus described this invention, I claim 105 and desire to protect by Letters Patent:

1. A time switch comprising a pair of parallel shafts, one of said shafts being adapted for rotation by a clock mechanism and the other being manually rotatable, and a plurality of pairs of contact fingers mounted on the respective 110 shafts for engagement when alined therebetween, each of said contact fingers being displaced both angularly and axially from the others on the same shaft.

2. A time switch comprising a pair of manually 115 rotatable contact assemblies, each comprising a shaft having a plurality of contact fingers mounted thereon and angularly and axially displaced from each other, and a third contact 120 assembly of similar character mounted therebetween, said third assembly being adapted for rotation by a clock mechanism and positioned to engage with said first mentioned pair at phases of its rotation determined by their respective 125 manually selected positions.

3. A time switch comprising a pair of manually 130 rotatable contact assemblies, each comprising a shaft having a plurality of contact fingers mounted thereon and angularly and axially displaced from each other, a third contact assembly 135 of similar character mounted therebetween, said third assembly being adapted for rotation by a clock mechanism and positioned to engage with said first mentioned pair at phases of its rotation determined by their respective manually selected positions, and means actuated by the engagement of said third assembly with one of said pair to connect the other of said pair for operation. 140

4. A time switch comprising a plurality of 145 parallel contact assemblies, each comprising a 150

shaft and a plurality of contact fingers helically disposed thereon, one of said assemblies being adapted for rotation by a clock mechanism and the others being manually rotatable, said clock 5 rotatable assembly being positioned to engage the others at phases of its rotation determined

by the respective manually selected positions of said other assemblies, and means actuated by the engagement of said clock rotatable assembly with one of said other assemblies for connecting a second of said assemblies for operation.
